UNITED STATES PATENT OFFICE.

HARRY A. ATWOOD, OF MILWAUKEE, WISCONSIN.

CHAIR.

1,346,932.

Specification of Letters Patent. Patented July 20, 1920.

Application filed March 23, 1920. Serial No. 367,993.

To all whom it may concern:

Be it known that I, HARRY A. ATWOOD, a citizen of the United States, and resident of Milwaukee, in the county of Milwaukee and State of Wisconsin, have invented new and useful Improvements in Chairs, of which the following is a description, reference being had to the accompanying drawings, which are a part of this specification.

10 My invention relates to certain new and useful improvements in chairs in general, but refers more particularly to features of novelty and advantage in chairs with adjustably yielding backs, such as are ordinarily used by stenographers.

15 This invention has for one of its objects to provide an improved manner of securing the usual cushion spring for the yielding back in position, so that the best possible results are obtained and a structure provided which will be comparatively inexpensive of production.

20 Another object of the present invention is to provide a chair iron for use with a chair of the type described, in which the amount of finishing work necessary after the same has been formed, preparatory to securing the same to a finished chair, is reduced to a minimum.

25 30 A further object of this invention is to provide an improved form of chair back carrying member, having its inner end concealed within a recess formed by the chair seat supporting frame, and having means integral therewith coöperating with the cushion spring to maintain same at a tension and thus yieldingly urge the back to its normal position.

35 40 A still further object of the present invention is to provide improved means for adjustably securing a back portion to the back staff, the back staff to the back staff supporting member, and means for limiting the movement of the back staff and its supporting member under action of the cushion spring. Besides, the accomplishment of these and other purposes, other salient features of the invention are the simplicity in structure, economy in manufacture, accessibility of adjustable parts and a construction of pleasing appearance.

45 50 With the above and other objects in view which will appear as the description proceeds my invention resides in the novel construction, combination and arrangement of parts substantially as hereinafter described

and more particularly defined by the appended claims, it being understood that such changes in the precise embodiment of the herein disclosed invention may be made as come within the scope of the claims.

55 In the accompanying drawings I have illustrated one complete example of the physical embodiment of my invention constructed according to the best mode I have so far devised for the practical application of the principles thereof, and in which:

Figure 1 is a side elevation of a chair embodying my invention, a portion of the supporting legs being broken away.

70 Fig. 2 is a rear elevation of the upper portion of the upright staff and back members adjustably carried thereby.

Fig. 3 is a fragmentary sectional view taken on the line 3—3 of Fig. 2.

75 Fig. 4 is a bottom plan view of the underside of the chair seat.

Fig. 5 is a sectional view taken through the chair seat on the plane indicated by the line 5—5 of Fig. 4.

80 Fig. 6 is a fragmentary top plan view of the inner end of the back staff supporting frame or arm, illustrating the manner of applying the tension of the cushion spring thereto to normally urge its outer end upwardly.

85 Fig. 7 is a perspective view of the improved form of collar member I employ for connecting the outer end of the cushion spring with the back staff supporting frame or arm, and

Fig. 8 is a fragmentary perspective view of the inner end of the back staff supporting frame or arm.

90 95 Referring now more particularly to the accompanying drawings, it will be perceived that the improved chair comprises a suitable supporting base composed of a plurality of legs 10, an adjustable threaded vertical post or shaft 11, the position of which may be regulated by an adjusting nut 12 and a seat frame on the top of the post having diverging forwardly extending arms 13 fastened to the bottom of seat 14 and a pair of shorter diverging rearwardly extending arms 15, likewise secured under the face of the seat.

100 105 These seat supporting spider arms are connected together beneath the middle of the chair by a web or hub portion 16 into an aperture of which the upper end of the threaded shaft post 11 is fitted.

110 As best shown in Figs. 1, 4 and 5, the seat

supporting spider is provided with a substantially central rectangular shaped spring receiving compartment 16' in which is projected the forward end of a fulcrumed frame 5 or arm 17. The arm 17 has its forward end bifurcated or forked to form side arm members 18 having two depending ears or lugs 19 apertured, as at 20, to receive a cross pin 21 having its ends secured in side wall portions 22 integral with the hub portion 16. The wall portions 22 define the spring compartment 16', and the cross pin 21 is secured therein just forwardly of the hub 16.

The extreme upper inner ends of the arms 18 of the frame 17, are connected together by a yoke portion 23 having a rounded projection 24 formed on its inner face at each end, for engagement with the inner spring collar 25 to be later described. The outer 20 end of the frame 17 is provided with a central vertically extending lug or rib 26, engageable in a recess 27 formed in the lower end of an upright back staff 28 secured thereto by fastening members 29. The rib 26 prevents lateral movement of the back staff and coact with the fastening members 29 to firmly secure the back staff to the frame 17.

As clearly shown in Figs. 4 and 5, the 30 front spider arms 13 are connected together by means of a transverse partition 30, provided with a central aperture 31 through which passes a tension or guide bolt 32, having its rear end passed between the arms 35 18 beneath the yoke 23. Mounted on the bolt 32 is a collar 33 retained from dislodgment therefrom by a head 34, and engaging the rear end of a cushion spring 35 coiled around the bolt 32 and having its forward 40 end engaged with the collar member 25 which is slidably mounted upon the bolt 32. The collar member 25 is formed with two lugs or ear members 36 positioned one on each side of the aperture through which the 45 bolt 32 passes, provided with notches or recesses 37, pivotally but readily detachably engageable with the rounded lugs 24 of the yoke member 23.

The spring 35 is maintained under tension by means of a handle or nut 38 in threaded adjusted engagement with the outer end of bolt 32, and by reason of the lugs 24 being positioned above the pivot of the frame 17, the tension of the spring 35 55 will at all times yieldingly urge the outer end of the frame upwardly.

The handle or nut 38 is so positioned that the operator of the chair may readily adjust or regulate the spring 35 without shifting 60 his or her position, the nut being positioned near the forward end of the chair seat.

The upward movement of the frame 17 under action of the spring 35 is adjustably limited by means of a substantially vertically adjustable abutment or stop screw 39

equipped with a turn handle 40 and a head 41, the screw 39 passing through an elongated aperture 42 in the arm 17. This adjusting screw 39 is carried by a rearwardly extending projection 43 formed on the hub 70 16 and is in threaded engagement with an aperture therein.

It will be readily understood that the adjustment of the screw 39 determines the forward limit of the travel of the seat back 75 because the upper end or head 41 of the screw, performs the function of the adjustable abutment or stop, before the staff 28 is free to swing rearwardly from such position under the cushioning and yielding restraint, 80 however, of the coil spring 35. Thus the degree of cushion spring action on the staff 28 may be determined or controlled by the handle nut 38 and the limit of forward swing of the staff regulated by screw 39.

The backward swinging movement of the back is limited by the engagement of the frame 17 with the top of the hub 16. If desired, in order to prevent garments from becoming caught in the back of the seat a 90 strap of leather 44 may be fastened to these two elements, see Figs. 1 and 5, thus bridging the gap and preventing the garments from entering the same.

As best shown in Figs. 1, 2 and 3, a back 95 rest 45 of any desired shape is vertically adjustably secured to the upper end of the back staff 28 by means of a guide plate 46 secured to the back 45 and having side parallel flanges 47 providing a guide channel in 100 which the upper end of the staff 28 passes. A binding or clamping bolt 48 passes through the upper end of the back staff and has its head passed through an elongated slot 49 in the guide plate 46 and has a 105 clamping nut on its outer threaded end, the bolt 48 firmly binding the guide plate 46 against the staff 28 when its nut 50 is tightened.

The bolt 48 is readily disengageable from the back portion 45 by raising the back portion its full upward limit of movement to register the enlarged end 49' of the guide slot with the bolt head to permit its removal therefrom. This structure is easier 115 to produce than structures now in every day use which contemplate the channeling or recessing of either the back 45 or staff 28.

What I claim as my invention is:

1. A chair iron comprising a seat portion 120 supporting frame, a chair back supporting member having its inner end pivotally connected to said supporting frame and its outer end connected with a chair back portion, a projection on the inner end of said chair 125 back supporting member above its pivotal connection with the supporting frame, a spring tension rod connected with said supporting frame and having its rear end rearwardly of the pivot of said chair back sup- 130

porting member, and a cushion spring having one end pressing against said projection and its other end pressing against the rear end of the tension rod.

2. A chair comprising a seat portion, a supporting frame secured thereto, a chair back portion, a chair back supporting member having its inner end bifurcated to form two securing arms and its outer end connected with the back portion, means pivotally connecting the securing arms with the supporting frame, a guide and tension rod having one end connected with the supporting frame and its other end disposed in the space between the securing arms above their pivots, a cushion spring mounted on the portion of said rod disposed between the securing arms, a collar member secured to the inner end of said rod and engaging the rear end of said spring, a second collar member slidably mounted on said rod intermediate its ends and engaging the forward end of said spring, and means connecting the second collar member with said securing arms whereby the cushion spring is confined between said collar members at a tension to normally urge the outer end of said back supporting member upwardly.

3. A chair comprising a seat portion, a supporting frame secured thereto, a chair back portion, a chair back supporting member having its inner end bifurcated to form two securing arms and its outer end connected with the back portion, means pivotally connecting the securing arms with the supporting frame, a guide and tension rod having one end connected with the supporting frame and its other end disposed in the space between the securing arms above their pivots, a cushion spring mounted on the portion of said rod disposed between the securing arms, a collar member secured to the inner end of said rod and engaging the rear end of said spring, a second collar member slidably mounted on said rod intermediate its ends and engaging the forward end of said spring, a transverse member connecting the inner ends of said securing arms, and rounded lugs formed on said transverse member and forming a pivotal connection between the transverse member and said second collar member.

4. A chair comprising a seat portion, a supporting frame secured thereto, a chair back portion, a chair back supporting member having its inner end bifurcated to form two securing arms and its outer end connected with the back portion, means pivotally connecting the securing arms with the supporting frame, a guide and tension rod having one end connected with the supporting frame and its other end disposed in the space between the securing arms above their pivots, a cushion spring mounted on the portion of said rod disposed between the securing arms, a collar member secured to the inner end of said rod and engaging the rear end of said spring, a second collar member slidably mounted on said rod intermediate its ends and engaging the forward end of said spring, a transverse member connecting the inner ends of said securing arms, and rounded lugs formed on said transverse member and forming a pivotal connection between the transverse member and said second collar member.

5. A chair iron comprising a seat portion supporting frame, a chair back supporting member having its inner end bifurcated and pivotally connected with the supporting frame and its outer end connected with a chair back portion, a transverse portion connecting the bifurcated end of said member above its pivotal connection with the supporting frame, a projection carried by said transverse portion, a tension rod having one end connected with said supporting frame and its other end passed beyond the pivotal connection of said chair back supporting portion with the supporting frame, a cushion spring, means connecting one end of said spring with the last mentioned end of said tension rod, and means pivotally connecting the other end of the spring with said projection, said spring normally urging said projection and last mentioned tension rod end apart to yieldingly urge the end of the supporting member connected with a chair back upwardly.

In testimony whereof, I affix my signature.

HARRY A. ATWOOD.
